SIGN EASEL

Bernard A. Slaugenhaupt, Chelan, Wash.

Application June 7, 1938, Serial No. 212,342

1 Claim. (Cl. 40—152.1)

This invention relates to sign easels and has for an object to provide an easel having a removable panel upon the front face of which a paper web may be supported for displaying an announcement of any type, there being a supply roller for the web disposed in rear of the panel so that by simply turning back a pair of fastening buttons the panel may be swung back to permit a fresh length of the web being disposed upon its front face when a new announcement is to be displayed.

A further object is to provide an easel having a panel provided with perforations to receive pins or other devices for displaying merchandise.

15 A further object is to provide a device of this character which will be formed of a few strong simple and durable parts, which will be inexpensive to manufacture, and which will not easily get out of order.

20 With the above and other objects in view the invention consists of certain novel details of construction and combinations of parts hereinafter fully described and claimed, it being understood that various modifications may be resorted to 25 within the scope of the appended claim without departing from the spirit or sacrificing any of the advantages of the invention.

In the accompanying drawing forming part of this specification,

30 Figure 1 is a front elevation of a sign easel constructed in accordance with the invention.

Figure 2 is a cross sectional view taken on the line 2—2 of Figure 1.

35 Figure 3 is a rear elevation of the sign easel with parts in section and parts removed.

Figure 4 is a detail cross sectional view taken on the line 4—4 of Figure 3.

40 Figure 5 is a rear elevation of a modified form of panel.

45 Referring now to the drawing in which like characters of reference designate similar parts in the various views, the easel is shown to comprise a frame including side members 10 and longitudinal members 11. The frame is supported at the ends by feet 12.

50 A panel 13 of laminated wood or other material is fitted at the edges into a rabbet 14 formed on the inner edges of the side and end members of the frame. A cleat 15 is disposed on the rear face of the panel for inserting and removing the panel from the frame. A pair of turnbuttons 16 are

pivotedly secured to screws 17 passed into the rear faces of the side members of the frame. These turnbuttons when turned to engage stops 18 on the rear face of the panel, hold the panel securely in place.

5 A pair of bracket arms 19 are disposed on the rear face of the lower longitudinal member 11 of the frame. A roller 20 is journaled at the ends in these bracket arms. A paper web 21 is wound upon the roller and this web is drawn under the bottom of the panel 13 after the turnbutton 16 has been released to permit the panel to be rocked rearwardly, and then the web is passed upwardly over the front face of the panel and terminally engaged in the rabbet on top of the panel. 10 When the panel is swung back into position and the turnbuttons turned to operative position the web will be securely held to present a writing surface upon which announcements may be written, the panel 13 forming a rigid support for the brush or writing tool while the announcement is being written. In some instances it may be desirable to display small or large articles of merchandise on the panel and to accomplish this a modified form of panel 22 is shown in Figure 5. 20 The panel is provided with stops 23 to receive the turnbuttons above described and is also provided with a grip for manipulating the panel. A plurality of perforations are formed in the panel and open through both faces of the panel to receive 30 pins or projections from which articles may be suspended for display on the panel.

25 From the above description it is thought that the construction and operation of the invention will be fully understood without further explanation.

What is claimed is:

35 A sign easel comprising a substantially rectangular frame, feet disposed transversely of the bottom of the frame for supporting the frame in upright position, a substantially rectangular panel in the frame, there being a rabbet formed in the bottom side of the frame receiving the lower edge of the panel, buttons swivelly secured on the frame and extending over the panel for removably securing the panel in the frame, a roller mounted upon the rear side of the frame below the panel, and a roll of paper carried by the roller extending over the front side of the panel and clamped between the frame and the edges of the panel.
